NON-DUSTING DETERGENT AND BLEACHING COMPOSITION

Jay C. Harris, Thomas C. Tesdahl, and Richard M. Anderson, Dayton, Ohio, assignors to Monsanto Chemical Company, St. Louis, Mo., a corporation of Delaware
No Drawing. Filed June 1, 1956, Ser. No. 588,614
15 Claims. (Cl. 252—99)

The present invention relates to detergent, bleaching, sterilizing, and disinfectant compositions which are non-dusting and which contain N,N-dichloro-p-toluenesulfonamide; trichlorocyanuric acid, or other "positive chlorine" containing organic compounds as an active constituent.

An object of the invention is to provide non-dusting compositions of improved stability containing N,N-dichloro-p-toluenesulfonamide (also known as Dichloramine T) or trichlorocyanuric acid in combination with alkaline salts, particularly alkaline phosphates and silicates. It is, accordingly, an object of the invention to provide dry compositions having reduced dusting characteristics, which are stable under ordinary conditions of storage and transportation and which, when dissolved in water, yield solutions suitable for washing, bleaching, sterilizing, and disinfecting.

A further object of the invention is to provide disinfecting detergents for use in cleaning containers, particularly metal vessels used in the bulk transport of milk, cream, and other milk products. An additional object of the invention is to provide detergents having stabilized disinfecting properties for use in hospitals or similar institutions, as well as in hotels and restaurants for dishwashing and other purposes.

Other objects and advantages of the invention will be apparent to those skilled in the art as the description proceeds.

It has been found desirable in the formulation of detergent, bleaching, sterilizing, and disinfectant compositions, to provide therein an active source of chlorine. N,N-dichloro-p-toluenesulfonamide and trichlorocyanuric acid are preferred compounds in this relationship. However, certain other types of organic chlorine-containing compounds are likewise of utility for this purpose.

The organic chlorine compounds contemplated in the present invention are those which contain a "positive chlorine" atom—i.e., a chlorine atom which has replaced an acidic hydrogen atom—with the result that the compound will hydrolyze in aqueous solution to yield hypochlorite ion.

One outstanding class of "positive chlorine" containing organic compounds are the N-chlorosulfonamides, and particularly the aryl sulfonamides. Examples of suitable compounds within this class are N,N-dichloro-p-toluenesulfonamide (also known as Dichloramine-T), N-chloro-p-toluenesulfonamide or the sodium salt thereof (known as Chloramine-T); p-(N,N-dichlorosulfonamide) benzoic acid, and the like.

Another outstanding class of "positive chlorine" containing compounds are those in which a chlorine atom has replaced the hydrogen of an activated imido group, and especially where the imido group has been activated by one or two acyl radicals connected directly to the nitrogen atom. Examples of suitable compounds of this type are the chlorine derivative of the keto form of cyanuric acid, N-chlorosuccinimide, N-chlorophthalimide, N,N-dichlorodimethylhydantoin, the chlorinated derivatives of melamine, ammeline, and ammelide, and numerous others which will be readily apparent to those skilled in the art.

Still another class of suitable "positive chlorine" con-

taining organic compounds for use according to the present invention are compounds in which chlorine atoms have replaced an acidic hydroxyl hydrogen. Suitable examples of such compounds are the enol form of trichlorocyanuric acid, the dihypochlorite of dihydroxyoctachlorobiphenyl, the hypochlorite of trichlorophenol, etc.

In preparing formulations for dishwashing and other washing operations, such as laundering, bleaching, sterilizing, and disinfecting, the foregoing "positive chlorine" containing organic compounds may be used in combination with other ingredients, such as water-soluble, alkaline phosphate compounds and/or certain water-soluble, silicate compounds, both of which are described more fully below.

The phosphate compounds are preferably chain polyphosphates. The polyphosphates are those phosphates containing more than one phosphorus atom per molecule, as distinguished from orthophosphates which contain only one phosphorus atom per molecule. Chain polyphosphates are non-cyclic (and usually linear) phosphates, as distinguished from ring or cyclic phosphates, such as trimetaphosphate and tetrametaphosphate. Examples of the more common chain polyphosphates are tetrasodium pyrophosphate and sodium tripolyphosphate, both of which can be obtained as essentially pure crystalline materials, and an amorphous polyphosphate known as sodium hexametaphosphate.

The amorphous polyphosphates, also known as glassy phosphates, are generally characterized either in terms of mole ratio of Na₂O to P₂O₅, or in terms of average chain length of the polyphosphate molecules in the glassy phosphate. For example, a commercial sodium hexametaphosphate has a mole ratio of Na₂O to P₂O₅ of about 1.13, and an average chain length of about 15 phosphorus atoms. In general, any of the water-soluble glassy polyphosphates, which have mole ratios of Na₂O to P₂O₅ ranging between about 5:3 and about 1:1 (corresponding to a range of average chain length from three to several thousands or higher) are suitable for use as the chain polyphosphate ingredient of the present invention.

While the immediately foregoing description has been in terms of sodium phosphates, it should be apparent that other alkali metal (particularly potassium) phosphates may be utilized in place of the corresponding sodium phosphates. It should also be pointed out that mixtures of two or more of the various chain polyphosphates described above can often be used to advantage in practicing the present invention.

A water-soluble silicate, such as sodium or potassium silicate is the other ingredient which may be utilized along with the above-described chlorine-containing compounds and chain polyphosphates in dry concentrates for aqueous wash solutions prepared according to this invention. As is well known, sodium silicates, for example, can vary quite widely in composition range from a mole ratio of Na₂O:SiO₂ of 1:4 to the more alkaline silicates, such as the orthosilicate having a mole ratio of Na₂O:SiO₂ ratio of 2:1. Mixtures of silicates having an overall molar ratio of Na₂O:SiO₂ between about 1:4 and 2:1 and preferably between about 1:3.5 and 1:1 can be utilized if desired.

In formulating and using the above mixtures of active chlorine compounds with phosphates and/or silicates, dusting is a major problem. However, it has been found that the addition of conventional dedusting agents, such as mineral oil, and other unsubstituted hydrocarbons results in the rapid deterioration of the available chlorine content.

It has now been found that the employment of certain silicone compounds in the present alkaline active chlorine formulations reduces the dusting tendency while at the same time avoiding objectionable deterioration of the

said chlorine-containing compound. The essential combination of the present invention comprises the said silicone with the active chlorine compounds. However, the invention also includes combinations of these essential components with phosphates and/or silicates as well as other ingredients.

It has now been found that the preparation of the above detergent bleaching, sterilizing and disinfecting compositions in dry form may be improved by the incorporation therein of certain silicones to control dusting. A preferred group are the methyl silicones, although ethyl and phenyl silicones as well as ethylphenyl silicones having both substituents, and also physical combinations of the above may similarly be employed. The methyl silicones which are employed in the present compositions have the general formula:

in which x represents the degree of polymerization influencing the viscosity of the composition. The viscosity of the silicones employed in the present invention may vary from 0.2 to 1,500 centistokes. The proportion of the said silicone may vary over a range of from 0.05% to 10% by weight, a preferred range being from 0.1% to 2.0% by weight of the overall composition.

The above-described silicones are advantageously formulated with an active chlorine-containing compound as a dry, granular concentrate which overcomes the inherent dustiness of the chlorine compound. Such dry concentrates may be utilized for further formulating. The ultimate compositions are then adapted to be added to an appropriate amount of water to form an aqueous solution used in washing, bleaching, sterilizing, disinfecting, etc.

The above discussed ingredients can be formulated into dry, granular concentrates suitable for addition to an appropriate amount of water to form aqueous solutions having utility as dishwashing solutions, laundry bleaches, disinfecting or deodorizing solutions. Such dry concentrates may, in general, be prepared in the following ranges of concentrations as broad ranges and preferred ranges expressed in percent by weight:

Component	Dishwashing Composition		Bleaching Composition		General Formula	
	Broad	Pfd.	Broad	Pfd.		
Phosphate.....	10-80	10-60	0-80	10-60	0-80	
Silicate.....	3-75	10-60	0-75	10-60	0-75	
Sodium sulfate, etc.....	0-60	20-60	0-75	20-60	0-75	
Active Cl Compound.....	0.1-10	0.1-8	0.1-99.9	0.1-50	0.1-99.9	
Silicone.....	0.1-10	0.1-5	0.1-10	0.1-5	0.1-10	

In general the dry formulations should have sufficient organic chlorine-containing compound to make the "positive chlorine" content fall in the following ranges:

	Dishwashing Composition, percent	Bleaching Composition, percent	General, percent
Broad range.....	0.05-5	0.05-43	0.05-43
Preferred range.....	0.1-2	2-5	0.1-5

Additional ingredients such as soda ash (e.g., 0-60%, and preferably 20-60% by weight), sodium sulfate, sodium chloride, dyes, perfumes, etc. can also be incorporated into the dry mixture if desired. However, the compositions must be kept free of any readily oxidizable or chlorinatable organic matter which would react with the organic chlorine-containing components of this invention.

Further details relative to the techniques and procedures to be followed in carrying out the process and utilizing

the compositions of the present invention can be readily understood by reference to the following examples:

Example 1

5 A sterilizing dishwashing composition was prepared employing the following components which were mixed in the dry state:

	Percent
N,N-dichloro-p-toluenesulfonamide.....	2
Sodium tripolyphosphate.....	50
Sodium metasilicate.....	25
Soda ash.....	23

The above formulation was tested as a control mixture relative to a similar formulation additionally containing 0.1% of a methyl silicone having a viscosity of 8 centistokes at 100° F. It was found that the mixture without the methyl silicone was very dusty, but that the formulation containing the said methyl silicone could be handled and dispensed in powder form without dusting or objectionable nasal irritation.

Example 2

The dishwashing composition of Example 1 was modified in a series of three samples by the use of 0.1% 25 methyl silicone having viscosities of 0.58, 1.7 and 13 centistokes (100° F.), respectively. It was found that each of the formulated detergents containing the methyl silicone dedusting agent was substantially free of dust in comparison to the control sample, which lacked the 30 silicone, and consequently dusted badly.

Example 3

A dishwashing formulation was prepared similar to that of Example 1, but employing 0.1% of an ethyl 35 phenyl silicone having a viscosity of 8 centistokes at 100° F. The detergent was found to be substantially free of dust.

Example 4

40 A bleach for laundering, disinfecting or deodorizing was prepared by dry blending the following ingredients (weight percent) as a typical example:

	Percent
Sodium tripolyphosphate.....	20
Sodium sulfate.....	69.8
Trichlorocyanuric acid.....	10
Methyl silicone.....	0.2

The above samples were subjected to an accelerated degradation test at 120° F. in which 35 days of accelerated degradation is equivalent to 8 to 18 months of normal storage. The test determines the effect of the dedusting agent upon the loss of available chlorine from the N,N-dichloro-p-toluenesulfonamide or trichlorocyanuric acid. A control test was also made using an oily material, e.g., 50 Nujol mineral oil. The table below shows the percentage loss of positive chlorine after 20 days and 35 days of storage at 120° F., and also provides identification data with respect to the various dedusting stabilizers employed.

60	Stabilizing Compound	Viscosity, Centistokes 100° F.	Loss of Positive Chlorine (percent)	
			20 Days	35 Days
Mineral oil.....		380 0.58	25 6	55 7
Methyl silicone.....		1.7 8	10 9	13 15
Ethylphenyl silicone.....		15 8	12 9	15 14

70 The above data indicate that an unsubstituted hydrocarbon, i.e., mineral oil, is ineffective as a dedusting agent, since the loss of available chlorine is very high. In contrast thereto the various silicone compounds show very small loss of chlorine despite the prolonged storage at 75 high temperature.

The above formulation, when dissolved in water, provides an active bleaching composition useful for bleaching cloth by treatment with such aqueous solution. The dry mixture, when contacted with water, produces hypochlorite chlorine.

What is claimed is:

1. A dry granular composition which comprises an active organic chlorine-containing compound in combination with a silicone selected from the group consisting of methyl silicones, ethyl silicones, phenyl silicones, ethylphenyl silicones and combinations thereof the proportion of the said silicone being from 0.05% to 10% by weight of the overall composition. 10

2. A dry granular composition which comprises an active organic chlorine-containing compound in combination with a methyl silicone, the proportions of the said silicone being from 0.05% to 10% by weight of the overall composition. 15

3. A dry granular composition which comprises an active organic chlorine-containing compound in combination with an ethylphenyl silicone, the proportion of the said silicone being from 0.05% to 10% by weight of the overall composition. 20

4. A dry granular composition which comprises an active organic chlorine-containing compound in combination with a silicone selected from the group consisting of methyl silicones, ethyl silicones, phenyl silicones, ethylphenyl silicones and combinations thereof, the said silicone having a viscosity of from 0.2 to 1,500 centistokes at 100° F., the proportion of the said silicone being from 0.05% to 10% by weight of the overall composition. 25

5. A dry granular composition which comprises an active organic chlorine-containing compound in combination with a methyl silicone, the said silicone having a viscosity of from 0.2 to 1,500 centistokes at 100° F., the proportion of the said silicone being from 0.05% to 10% by weight of the overall composition. 30

6. A dry granular composition which comprises an active organic chlorine-containing compound in combination with an ethylphenyl silicone, the said silicone having a viscosity of from 0.2 to 1,500 centistokes at 100° F., the proportion of the said silicone being from 0.05% to 10% by weight of the overall composition. 40

7. A dry granular composition which comprises N,N-dichloro-p-toluene sulfonamide in combination with a silicone selected from the group consisting of methyl silicones, ethyl silicones, phenyl silicones, ethylphenyl silicones and combinations thereof, the said silicone having a viscosity of 0.2 to 1,500 centistokes at 100° F., the proportion of the said silicone being from 0.05% to 10% by weight of the overall composition. 50

8. A dry granular composition which comprises N,N-dichloro - p - toluenesulfonamide in combination with a methyl silicone having a viscosity of 0.2 to 1,500 centistokes at 100° F., the proportion of the said silicone being from 0.05% to 10% by weight of the overall composition. 55

9. A dry granular composition which comprises N,N-dichloro-p-toluenesulfonamide in combination with an ethylphenyl silicone having a viscosity of 0.2 to 1,500 centistokes at 100° F., the proportion of the said silicone being from 0.05% to 10% by weight of the overall composition. 60

10. A dry granular composition which comprises trichlorocyanuric acid in combination with a silicone selected from the group consisting of methyl silicones, ethyl silicones, phenyl silicones, ethylphenyl silicones and com-

bination thereof, the said silicone having a viscosity of from 0.2 to 1,500 centistokes at 100° F., the proportion of the said silicone being from 0.05% to 10% by weight of the overall composition.

5 11. A dry granular composition which comprises trichlorocyanuric acid in combination with a methyl silicone having a viscosity of 0.2 to 1,500 centistokes at 100° F., the proportion of the said silicone being from 0.05% to 10% by weight of the overall composition.

12. A dry granular composition which comprises trichlorocyanuric acid in combination with an ethylphenyl silicone having a viscosity of 0.2 to 1,500 centistokes at 100° F., the proportion of the said silicone being from 0.05% to 10% by weight of the overall composition.

13. A dry granular composition which comprises between about 25% and about 60% of sodium tripolyphosphate, between about 10% and 60% of sodium silicate, between about 20% and 60% of sodium sulfate, between about 0.05% and 10% of an active organic chlorine-containing compound and about 0.1% to 10% by weight of a silicone selected from the group consisting of methyl silicones, ethyl silicones, phenyl silicones, ethylphenyl silicones and combinations thereof, the said silicone having a viscosity of from 0.2 to 1,500 centistokes at 100° F.

14. A dry granular composition which comprises between about 10 and about 60 weight percent of sodium tripolyphosphate, between about 20% and about 60% of sodium sulfate, sufficient trichlorocyanuric acid to make the chlorine content of the said composition equal to between about 2 and about 5% of said composition, and about 0.05% to about 10% by weight of a methyl silicone having a viscosity of 0.2 to 1,500 centistokes at 100° F.

15. The method of inhibiting the decomposition of active organic chlorine-containing compounds which comprises contacting the same with a silicone selected from the group consisting of methyl silicones, ethyl silicones, phenyl silicones, ethylphenyl silicones and combinations thereof, the said silicone having a viscosity of from 0.2 to 1,500 centistokes at 100° F. the said silicone being employed in the proportions of from about 0.05% to about 10% by weight of the overall composition.
